UNITED STATES PATENT OFFICE.

CHARLES F. GREGG AND EMIL PROBST, OF INDIANAPOLIS, INDIANA.

DRYING MACHINE.

Application filed July 30, 1926. Serial No. 125,836.

The object of our invention is to produce an efficient device by means of which garments which have been freshly cleaned may be quickly aerated and dried without tangling or injury.

The accompanying drawings illustrate our invention.

Fig. 1 is a plan; Fig. 2 a vertical section, on a larger scale; Fig. 3 a fragmentary vertical section on the scale of Fig. 1, in a plane at right angles to that of Fig. 2; Fig. 4 a section on the scale of Fig. 1 and on line 4-4 of Fig. 2, and Fig. 5 a fragmentary sectional detail, on a smaller scale, of the connections with the fan eye.

In the drawings 10 indicates a rotary basket having reticulated bottom and top walls, the top wall being conveniently formed in part of a movable section which may be shifted to give access to the interior of the basket. The side walls 11, of basket 10 are preferably imperforate.

Basket 10 is carried by a rotary vertical shaft 12 rotated at low speed by gearing 13 from a drive shaft 14, and is contained within an outer casing 15 having an opening in its side closed by doors 16 above the top of basket 10.

Arranged below casing 15 is a blower fan 17 the discharge pipe of which leads through an opening 18 in the bottom of casing 15. The effective size of opening 18 may be varied by the flap-valve 19.

Fan 17 is driven by belt 20 from shaft 14 and its eye is connected to a duct 21 within which is mounted a damper 22.

Duct 21 leads from a chamber 23 within which heating coil 24 is mounted. Leading into duct 21 is a cold air duct 25 and a flap-valve 26 is so arranged in duct 21 as to control flow thereto from duct 25 and chamber 23.

Formed through the bottom of chamber 15 on the approach side of opening 18 is a slot 30 beneath which is arranged a removable drawer 31. Secured to the under side of the bottom of basket 10 is a radially arranged sweeper 32 which drags on the bottom of chamber 15 and serves to sweep lint, buttons, etc. into drawer 31.

In operation, garments to be aerated are placed in basket 10 and the basket and fan are then rotated. As successive portions of the basket arrive above opening 18 the blast of air therefrom lifts the superjacent garments and aerates and dries them without

tangling. As successive portions of the basket pass the air blast the superjacent clothes drop to their original positions.

We claim as our invention:

1. A garment drier comprising a horizontally rotary basket having a perforated bottom, a fan having a discharge duct leading to a limited area beneath and closely subjacent the bottom of the basket, and eccentric to the axis thereof, and means by which the basket and fan may be rotated.

2. A garment drier comprising a horizontally rotary basket having a perforated bottom, a casing within which said basket is mounted, a fan having a discharge duct through the bottom of the casing leading to a limited area beneath and closely subjacent the bottom of the basket, and eccentric to the axis thereof, and means by which the basket and fan may be rotated.

3. A garment drier comprising a horizontally rotary basket having a perforated bottom, a fan having a discharge duct leading to a limited area closely subjacent the bottom of the basket, a sweeper carried by the basket and sweeping the bottom of the casing over a slot formed therethrough, and means by which the basket and fan may be rotated.

4. A garment drier comprising a horizontally rotary basket having a perforated bottom, a casing within which said basket is mounted, a fan having a discharge duct through the bottom of the casing leading to a limited area closely subjacent the bottom of the basket, a sweeper carried by the basket and sweeping the bottom of the casing over a slot formed therethrough, and means by which the basket and fan may be rotated.

5. A garment drier comprising a horizontally rotary basket having a perforated bottom, and a discharge nozzle delivering air under pressure to a limited area beneath said basket at a point eccentric to the axis thereof and upwardly through the bottom of said basket.

6. A garment drier comprising a horizontally rotary basket having a perforated bottom, an air discharge duct delivering air upwardly through said bottom eccentric to the axis thereof to a limited area in said bottom and means for rotating said basket.

7. A garment drier comprising a horizontally rotary basket having a perforated bottom and an air discharge duct delivering air upwardly at an angle less than a right

angle to said bottom through said bottom eccentric to the axis thereof to a limited area in said bottom.

8. A garment drier comprising a horizontally rotary basket having a perforated bottom, a fan having a discharge duct leading to a limited area beneath and closely adjacent the bottom of the basket and delivering air through said basket at an angle less than

a right angle to the bottom of the basket ¹⁰ and eccentric to the axis thereof and means by which the basket may be rotated.

In witness whereof, we have hereunto set our hands at Indianapolis, Indiana, this 27th day of July, A. D. one thousand nine ¹⁵ hundred and twenty-six.

CHARLES F. GREGG.
EMIL PROBST.
